LOCK SEAL LID

Filed Aug. 6, 1946

2 Sheets-Sheet 2

tures of construction, and novel combinations of parts, for which protection is desired.

In said drawings:

Fig. 1 is a vertical section on the line 1—1, Fig. 2, through the outer end of a standard journal box showing my novel lid including the frame and cover plate applied thereto and showing the cover plate in closed position.

Fig. 2 is a front elevation of the parts shown in Fig. 1.

Fig. 3 is a view similar to Fig. 1 but showing the cover plate in open position.

Fig. 4 is a vertical section on the line 4—4, Fig. 3.

Fig. 5 is an inside view of the cover plate, detached.

The drawings show my novel lid applied to a journal box for illustrative purposes only. As shown in Fig. 1, the standard journal box J has a rough cast open outer end, over which opening my novel lid is attached, the opening being usually formed during the casting operation and left unfinished. The journal box J is provided with a standard hinge lug J' on its top above the open end, said hinge lug J' being provided with a bore J2 for a hinge pin 2 for the lid, the top of the lug J' being formed in a substantially horizontal plane, as indicated at J3 (Figs. 1 and 3), while the outer face of lug J' slopes downwardly and inwardly as at J4 to form an acute angle with the top surface J3, i. e., an angle of less than 90 degrees, as shown in Figs. 1 and 3. The above is standard practice, substantially all journal boxes being formed in the above manner, and hence the box J, per se, forms no part of my present invention.

Around the opening is a frame member 1 of rectangular shape, shown more particularly in Figs. 3 and 4, the same having an opening substantially conforming with the size and shape of the outer opening of the journal box J, said frame being of greater width and height than the thickness of the lip around the opening of the journal box, as shown in Fig. 3.

At the lower end of the frame 1 is a curved resilient spring steel tongue 1a, extending within the lower end of the opening in the journal box J and having its free end engaging the inner lower curved wall of said box, so as to conform to casting thickness and any irregularities in casting form, as indicated in Figs. 1 and 3, whereby the lower end of the frame 1 will be prevented from moving away from the lower portion of the opening in the box J. Tongue 1a is placed at the center of the lower end of frame 1 thereby leaving a free space through the frame at both sides of the tongue to provide space for packing irons. At the upper end of the frame 1 are a pair of resilient hinge eyes 1b (Fig. 4), preferably formed of resilient sheet metal bent to such shape that the axes of the eyes 1b are normally slightly offset outwardly from the axis of the bore J2 of the hinge lug J', whereby when the hinge pin 2 is passed through the eyes 1b and through the bore J2 of hinge lug J' the sheet metal eyes 1b will be deflected so as to forcibly pull the upper edge of the frame 1 towards and against the upper portion of the opening in the casting box J, the action of the eyes 1b and the resilient tongue 1a serving to tightly clamp the upper and lower ends of frame 1 against and across the opening in the casting box J.

As shown, the inner face of frame 1 is provided with a peripheral groove 1c, which is deeper at the lower end than at the upper end, the sides

being inclined as shown in Fig. 3 with respect to the outer face of the frame 1, whereby the upper end of the frame 1 will clear the outer face of the hinge lug J' of the journal box casting J, the upper end of frame 1 terminating below the front face of the hinge lug J'. Within the peripheral recess 1c is a felt or other gasket 3 of substantial thickness, adapted to contact squarely the lip around the opening of the journal box casting J so as to form an effective seal, as indicated in Figs. 1 and 3. Around the peripheral portion of the outer face of frame 1 is a recess 1d of substantial depth receiving a correspondingly shaped gasket 4, which projects outwardly beyond the outer face of the frame 1, for the purpose hereinafter set forth. The upper run of gasket 4 is narrower than at the sides and lower run to provide for the upper end of frame 1 fitting between the lip of casting J at the top of the opening and the front face of lug J'.

In connection with the frame 1, I provide a closure plate 5, shown more particularly in Figs. 2 and 5, said lid being of slightly larger overall size than the frame 1, and having inturned flanges 5a (Fig. 5) at its sides and bottom, while the upper edge of the plate 5 is left unflanged but projects over the frame at the top. At the top center of the cover plate 5 is a substantially U-shaped offset portion 5b which may be formed by pressing out the material of the plate 5, said offset 5b extending upwardly beyond the upper edge of the plate 5 proper, as shown in Figs. 1, 2 and 3, and overlying the hinge lug J' of the journal box J, the upper end of the portion 5b being rounded as at 5c for this purpose. The offset 5b, 5c is spaced from hinge lug J' a distance to provide sufficient clearance for operation of the spring 6 hereinafter described, and at the same time to exclude dirt and moisture from the hinge lug J'. Moreover, the upper end 5d (Fig. 3) of offset 5b acts as a stop to limit opening of the cover plate 5 to substantially horizontal position, end 5d engaging the back of lug J' when cover 5 is opened as in Fig. 3 but clearing the top of lug J' when cover 5 is closed as in Fig. 1. Within the offset portion 5b is secured, by rivets 6a or by welding or the like, a strong flat spring 6 adapted to yieldably engage the top horizontal surface J3 of the hinge lug J' of casting J, as shown in Fig. 1 when the cover 5 is opened, as in said figure.

As shown the upper free end of spring 6 is provided with a return bend or loop 6b having an offset 6c adjacent its free end and having its free end rounded as at 6d so that when the cover plate 5 is closed as shown in Fig. 1, the spring will entirely clear the front face J4 of lug J' so that return bend 6b does not contact therewith. But when cover plate 5 is in open position, as shown in Fig. 3, the return bend portion 6b of spring 6 will seat squarely upon the top horizontal face J3 of lug J' and due to flexing of spring 6 will yieldably maintain the cover plate 5 in open position. This arrangement of spring 6 provides for easy opening of plate 5 and eliminates lug wear, the sole function of spring 6 being to hold the cover plate 5 open in substantially horizontal position shown in Fig. 3, the return bend 6b clearing the front face J4 of lug J' during opening and closing of the plate 5 due to the curved portions 6c and 6d at the free end of return bend 6b which makes this action possible.

Extending from the upper edge of the cover plate 5 are a pair of resilient hinge eyes 5e (Figs.

2 and 4 is spaced so as to be disposed beside the hinge eyes 5b of frame 4, said eyes 5b being likewise formed of spring steel and being normally offset outwardly from the axis of the hinge pin 2 so that when the hinge pin 2 is passed through the eyes 5b and the eyes 1b and through the hinge lug J of the casting J in the normal manner, the resiliency of the eyes 5b will, due to the shifting of the position of the eyes 5b, forcibly pull the upper edge of the cover plate 5 when closed into close contact with the gasket 4 on the outer face of frame 4 as shown in Fig. 1, so as to prevent moisture and dust from entering between cover plate 5 and the frame 4 adjacent the upper portion thereof (not shown) to the ragged end 3015.

Preferably on the inner side of the cover plate 5 is an inwardly offset portion 5f which may be conveniently formed by die-pressing during the forming of the cover 5, said offset serving as an oil-drip ledge to direct any oil splashed onto the inner side of the cover plate 5 downwardly and inwardly back into the journal box.

At the lower edges of cover plate 5 is a spring steel strap 7 preferably secured by rivets 1a, said strap extending below the bottom of frame 4 and being flanged inwardly at 7b and bent to form an eye 1c which underlies the lower inner edge of frame 4 as shown in Fig. 1, the strap beyond a said eye 1c extending downwardly and inwardly as at 1d to form an integral handle for raising the cover plate 5. In the eye 1c is journaled a shaft 8 carrying at each end a roller 8a adapted to make a rolling contact against the inner lower edge of frame 4 as shown in Fig. 1, the shaft 8 revolving freely in eye 1c when the plate 5 is opened or closed. The above arrangement provides a combined spring catch, lock and roller door lift handle, and being formed of spring steel provides for easy opening and closing of the cover plate 5, also provides for tight locking of the plate 5 in closed position, same providing a positive catch and lock by reason of the rollers 8a hooking under the frame 4 by a slight upward pull on handle 1d, will pull the eye 1c and rollers 8a from under the frame allowing easy lifting of the lid. Rollers 8a prevent undue wear on the frame and provide for easy operation. When in closed position the cover 5 will be maintained tightly closed against the gasket 4 of the frame by action of the lug rollers 8a at the lower end of the cover plate 5, together with the upward pull of the resilient hinge eyes 5b of the cover plate 5 acting on the hinge pin 2.

As shown in Figs. 2 and 4, the pointed end of hinge pin 2 is split as at 2a but slightly off-centered, and a chisel recess 2b is provided in the thicker side of the split 2a whereby when a chisel is inserted in recess 2b and swung, the pointed end of the pin 2 at the thin side may be readily spread to prevent removal of pin 2.

By the above construction, I provide a lock-seal journal lid which may be made of standard dimensions and suitable for different tonnages of journal boxes which carry different sizes of journals and bearings, my lid includes a frame felted on the casting face or side so that when locked down it seals the opening between the frame and the rough cast rim of the journal box J, making the connection moisture and dust-proof.

The tongue 1a at the lower end of frame 4 fits over the inner slope of the journal box J and serves to lock the lower end of the frame securely to the casting when the hinge pin 2 is driven through both casting lug J and hinge eyes 1b. However, the frame 4 is demountable and inter-changeable on different castings. Since the open-

ing in the frame 4 is substantially equal to the opening in the journal box, the frame will not interfere with packing operations, or packing irons, while the packing or rolls are being set up or replaced. The two hinge eyes 1b of the frame 4 at the top thereof are offset shorter than the lug hole J2, so that when the pin 2 is driven in, it will cause the eyes 1b to be shifted inwardly and in that way lock the top of frame 4 tightly against the casting J and at the same time lock the tongue 1a in the journal box casting, thus sealing permanently with the felt liner 3 the frame 4 to the casting, independently of the cover plate 5. By inclining the recess 1c for the felt 3, the frame 4 will clear all standard journal box lugs J. The frame 4 may be die-pressed, molded, cast or otherwise formed from metal or other suitable material, with its outer or cover-engaging face made to contact the cover plate 5b which latter is hinged to the same pin 2.

The felts 3 and 4 may be of any desired material that is yieldable and flexible, so that when the cover plate 5 is closed against the frame 4, it will act as an absolute dust-tight, waterproof seal. The felt or other yieldable material 3 and 4 will act as a seal between the frame 4 and the cover plate 5 and will act as a shock absorber to prevent vibration.

I thus provide a cover 5 in combination with a frame 4 and pin 2 to form a unit which when properly assembled together on the journal box will form a lock-seal lid therefor. The cover plate 5 may be stamped or die-pressed, cast, molded, or otherwise formed of metal or other suitable material with edges slightly turned to act as a water shed and to prevent foreign material from entering between the frame 4 and cover 5, the hinge eyes thereof being preferably made of strong spring steel riveted, spot-welded or otherwise attached to the cover plate 5, so as to

The cover 5 operates independently of the frame 4 and rises when opened above the journal box lug as shown in Fig. 3, and is held in place by the spring 6 which contacts the top surface J3 of the journal box lug. When the cover 5 is closed, it excludes dust and water from entering the journal box contact with the gasket 4, and by reason of the locking rollers 8a the cover 5 when closed will clamp under the lower edge of the frame 4, so as to seal tightly a

I do not limit my invention to the exact form shown in the drawings, for obviously changes may be made therein within the scope of the claims. Moreover, the journal box or bulk-car door may be cast with the frame 4 forming an integral part thereof, thereby necessitating use only of my novel cover plate 5 to form a lock-seal lid. The frame and cover may be made in different sizes to fit any size standard journal box or bulk-car door.

1. In a lock-seal lid for journal boxes or the like having a bottom wall sloping upwardly and outwardly and terminating at an opening in the outer end of the box, and having a central hinge lug on its top wall above said opening carrying a horizontally disposed hinge pin, said lug having a substantially horizontal top face, and said box having a frame around the box opening, a gasket around the outer face of the frame projecting beyond said face, a cover plate hinged on said pin and adapted to overlie the frame, means on the cover plate for yieldably maintaining the upper end of the plate in tight con-

tact with the frame when the plate is in closed position; handle means on the lower end of said plate having a portion yieldably engaging the frame for locking the cover plate in tight contact with the gasket when the plate is in closed position, and means on the cover plate yieldably engaging the top face of the hinge lug when the plate is in open position to hold the plate in said position.

2. In a lid as set forth in claim 1, said maintaining means comprising hinge eyes at opposite sides of the hinge lug and secured to the upper end of the plate by resilient metal straps, the eyes being normally offset from the frame a distance less than the actual distance of the upper end of the cover from the axis of the hinge pin, whereby the straps will be flexed when the hinge pin passes through the eyes to forcibly draw the upper end of the plate toward the frame.

3. In a lid as set forth in claim 1, said cover plate having a centrally disposed outwardly offset portion extending above the upper edge of the cover to form a hood and an abutment which contacts the lug to limit the opening of the cover, the hood being curved to overlie the hinge lug; and said holding means on the plate comprising a flat steel spring secured at its inner end to a point within said offset portion and having its outer end adapted to engage the top face of the hinge lug only when the cover plate is open.

4. In a lid as set forth in claim 1, said locking means comprising a resilient strap extending below and in rear of the lower end of the frame and having an eye disposed adjacent the lower inner edge of the frame, the strap beyond the eye extending downwardly to form a resilient handle; and a roller journaled in the eye adapted to contact the back of the frame when the cover is closed.

5. A lock-seal lid for journal boxes or the like having a bottom wall sloping upwardly and outwardly and terminating at an opening in the outer end of the box, and having a central hinge lug on its top wall above said opening carrying a horizontal hinge pin, said lug having a substantially horizontal top face, comprising a frame hinged on said pin and having an opening therein corresponding in area with the box opening; a gasket around the inner face of the frame adapted to engage the end of the box around said box opening; means for yieldably maintaining the frame in tight contact with the box end; a second gasket around the outer face of the frame projecting beyond said face; a cover plate hinged on said pin and adapted to overlie the frame; and means on said plate yieldably maintaining the upper end of the plate in tight contact with the second gasket when the plate is in normal closed position; handle means on the lower end of the plate having a portion yieldably engaging the frame for locking the cover plate in tight contact with the second gasket when the plate is closed; and means in the cover plate yieldably engaging the top face of the hinge lug when the plate is in open position to hold the plate in said position.

6. In a lid as set forth in claim 5, said frame having a peripheral groove in its inner face receiving the first gasket, said groove being shallower at the upper end of the frame than at the lower end, whereby the upper end of the frame will clear the said hinge lug.

7. In a lid as set forth in claim 5, said frame

5 maintaining means comprising a downwardly and inwardly inclined tongue at the lower end of the frame adapted to enter the box opening and to contact the upwardly and outwardly inclined bottom wall of the box adjacent the opening, to maintain the first gasket tightly compressed between the lower end of the frame and the end of the box.

8. In a lid as set forth in claim 5, said frame 10 maintaining means comprising hinge eyes at opposite sides of the hinge lug and secured to the upper end of the frame by resilient metal straps, the eyes being normally offset from the frame a distance less than the actual distance of the upper end of the frame from the axis of the hinge pin, whereby the straps will be flexed when the hinge pin passes through the eyes to forcibly draw the upper end of the frame towards the box.

9. In a lid as set forth in claim 5, said frame 15 maintaining means comprising a downwardly and inwardly inclined tongue at the lower end of the frame adapted to enter the box opening and to contact the upwardly and outwardly inclined bottom wall of the box adjacent the opening, to maintain the lower end of the frame in tight contact with the end of the box; and hinge eyes at opposite sides of the hinge lug and secured to the upper end of the frame by resilient metal 20 straps, the eyes being normally offset from the frame a distance less than the actual distance of the upper end of the frame from the axis of the hinge pin, whereby the straps will be flexed when the hinge pin passes through the eyes to forcibly draw the upper end of the frame towards the box.

10. In a lid as set forth in claim 5, said cover 25 maintaining means comprising hinge eyes at opposite sides of the hinge lug and secured to the upper end of the cover by resilient metal straps, the eyes being normally offset from the frame a distance less than the actual distance of the upper end of the cover from the axis of the hinge pin, whereby the straps will be flexed when the hinge pin passes through the eyes to forcibly draw the upper end of the cover plate towards the box.

11. In a lid as set forth in claim 5, said cover 30 maintaining means comprising hinge eyes at opposite sides of the hinge lug and secured to the upper end of the cover by resilient metal straps, the eyes being normally offset from the frame a distance less than the actual distance of the upper end of the cover from the axis of the hinge pin, whereby the straps will be flexed when the hinge pin passes through the eyes to forcibly draw the upper end of the cover plate towards the box when the cover is in closed position.

12. In a lid as set forth in claim 5, said locking 35 means comprising a resilient strap extending below and in rear of the lower end of the frame and having an eye disposed adjacent the lower inner edge of the frame, the strap beyond the eye extending downwardly to form a resilient handle; and a roller journaled in the eye adapted to contact the back of the frame when the cover is closed.

13. A lock-seal lid for journal boxes or the like 40 having a bottom wall sloping upwardly and outwardly and terminating at an opening in the outer end of the box, and having a central hinge lug on its top wall above said opening carrying a horizontal hinge pin, said lug having a substantially horizontal top face; comprising a frame hinged on said pin and having an opening there- 45 in corresponding in area with that of the box

opening, a gasket around the inner face of the frame adapted to engage the end of the box around said box opening; means for yieldably maintaining the frame in tight contact with the box end; a second gasket around the outer face of the frame projecting beyond said face; a cover plate hinged on said pin and adapted to overlie the frame; means on said plate yieldably maintaining the upper end of the plate in tight contact with the second gasket when the plate is in normal closed position; means yieldably engaging the top face of the hinge lug when the plate is in open position to hold the plate in said position; and handle means on the lower end of the plate having a portion adapted to engage the frame to maintain the plate in closed position.

14. In a lid as set forth in claim 13, said frame maintaining means comprising a downwardly and inwardly inclined tongue at the lower end of the frame adapted to enter the box opening and to contact the upwardly and outwardly inclined bottom wall of the box adjacent the opening, to maintain the first gasket tightly compressed between the lower end of the frame and the end of the box.

15. In a lid as set forth in claim 13, said frame maintaining means comprising hinge eyes at opposite sides of the hinge lug and secured to the upper end of the frame by resilient metal straps, the eyes being normally offset from the frame a distance less than the actual distance of the upper end of the frame from the axis of the hinge pin, whereby the straps will be flexed when the hinge pin passes through the eyes to forcibly draw the upper end of the frame towards the box.

16. In a lid as set forth in claim 13, said cover maintaining means comprising hinge eyes at opposite sides of the hinge lug and secured to the upper end of the cover by resilient metal straps,

the eyes being normally offset from the cover a distance less than the actual distance of the upper end of the cover from the axis of the hinge pin, whereby the straps will be flexed when the hinge pin passes through the eyes to forcibly draw the upper end of the cover plate towards the box when the cover is in closed position.

17. In a lid as set forth in claim 13, said cover plate having a centrally disposed outwardly offset portion extending above the upper edge of the cover to form a hood and an abutment which contacts the lug to limit the opening of the cover, the hood being curved to overlie the hinge lug; and said holding means on the plate comprising a flat steel spring secured at its inner end to a point within said offset portion and having its outer end adapted to engage the top face of the hinge lug only when the cover is open.

18. In a lid as set forth in claim 13, said locking means comprising a resilient strap extending below and in rear of the lower end of the frame and having an eye disposed adjacent the lower inner edge of the frame, the strap beyond the eye extending downwardly to form a resilient handle; and a roller journaled in the eye adapted to contact the back of the frame when the cover is closed.

DONALD D. BRYANT.
